UNITED STATES PATENT OFFICE.

PALEMON H. GASKINS, OF JACKSONVILLE, FLORIDA.

LUBRICATING SYSTEM.

Original application filed January 10, 1921, Serial No. 436,207. Divided and this application filed August 25, 1921, Serial No. 436,438.

To all whom it may concern:

Be it known that I, PALEMON H. GASKINS, a citizen of the United States, and a resident of Jacksonville, in the county of Duval and State of Florida, have invented certain new and useful Improvements in Lubricating Systems, of which the following is a specification.

My invention relates in general to lubricating systems and more particularly to a lubricating system for the shackle connections of vehicle spring suspensions such as shown in my co-pending application for lubricating systems, filed January 10, 1921, Serial No. 436,207, of which this application is a division.

The object of my invention is to provide a lubricating system of this character which maintains a film of oil or other lubricant between all of the relatively movable parts of the shackle connection of the spring suspension, thereby reducing wear, eliminating noise and insuring even, smooth and easy action of the shackle connection.

Another object is to provide a lubricating system of this character which is extremely simple and durable in construction, reliable in operation and easy and inexpensive to manufacture and maintain.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a fragmentary view in side elevation, illustrating the invention embodied in the spring suspension of a motor vehicle;

Figure 2 is a fragmentary view in longitudinal vertical section, parts being shown in elevation for the sake of illustration; and

Figure 3 is a view in transverse vertical section, on line 3-3 of Figure 2.

Referring to the drawings wherein for the sake of illustration is shown the preferred embodiment of the invention, a portion of one of the side members of the chassis of a motor vehicle is designated generally at C and comprises a channeled construction including a body portion c^1 and side flanges c^2 and c^3 . A spring suspension, including a leaf spring L, is associated with

the chassis, one end of the leaf spring being pivotally secured to the side member of the chassis by a shackle connection, designated generally at S.

The shackle connection S includes an upper shackle bolt 10 extending through suitable openings provided therefor in the side flanges c^2 and c^3 of the side member of the chassis and a lower shackle bolt 11 extending through the eye L' of the leaf spring. Hangers or links 12 and 13 are pivotally connected at their ends to the shackle bolts, the link 12 being confined between the heads of the shackle bolts and the chassis and spring and the link 13 being maintained in proper position on the shackle bolts by means of nuts 14 and 15 threaded on the shackle bolts 10 and 11. Washers 16 and 17 are preferably interposed between the nuts 14 and 15 and the adjacent portions of the link 13. A bushing 19 is mounted on the lower shackle bolt 12 between the shackle bolt and the eye L' of the leaf spring L.

The shackle bolts 10 and 11 are of identical construction and are each provided with axial bores, designated at 10^a and 11^a, respectively, radial bores 10^b and 11^b communicating with said axial bores and disposed approximately centrally of the shackle bolts and peripheral grooves 10^c and 11^c communicating with the radial bores 10^b and 11^b, respectively.

Means is provided for supplying lubricant to said shackle bolts and includes a sleeve 20 mounted on the portion of the upper shackle bolt 10 comprehended between the side flanges c^2 and c^3 and a lubricant supply pipe 21 arranged in the channel of the chassis and conveying a supply of lubricant under pressure from a reservoir or other suitable source of supply. A branch 22 extends from the supply pipe 21 through the bushing 20 and communicates with the peripheral groove 10^c of the upper shackle bolt.

A pipe connection 24 has one end offset and threaded into the axial bore 10^a of the upper shackle bolt 10 and its other end similarly offset and threaded into the axial bore 11^a of the lower shackle bolt 11. The pipe connection 24 affords a free and unobstructed conduit through which the lubricant may flow directly from the axial bore of the upper shackle bolt 10 into the axial bore of the lower shackle bolt 11.

In operation, the lubricant flows through the supply pipe 21 under pressure and from the branch 22 thereof is fed into the peripheral groove 10^c of the upper shackle bolt 10. 5 From the peripheral groove 10^c a part of the lubricant is distributed over the surface of the upper shackle bolt and over the contacting surfaces of adjacent relatively movable parts and the remainder of the lubricant 10 flows through the radial bore 10^a, axial bore 10^a and pipe connection 24 into the axial bore 11^a of the lower shackle bolt and thence through the radial bore 11^b thereof into the peripheral groove 11^c from whence it is distributed 15 over the contacting surfaces of the adjacent relatively movable parts. In this manner a film of oil is maintained between all of the relatively movable parts thus greatly reducing wear, eliminating noises and insuring smooth, even and easy action. 20

I claim:

1. In a lubricating system, a shackle connection including an upper shackle bolt and a lower shackle bolt, each of said shackle bolts having an axial and a radial bore communicating with each other and a longitudinal groove in its periphery communicating with the radial bore, means for supplying lubricant to the peripheral groove of the upper shackle bolt in such manner that a portion of the lubricant is utilized to lubricate the upper shackle bolt and another portion of the lubricant is conveyed to the axial and radial bores of the upper shackle bolt, 25 and a pipe having threaded connection with the ends of the shackle bolts and having direct, free and open communication with the axial bores of said shackle bolt for conveying the lubricant from the axial bore of the upper shackle bolt directly to the axial bore of the lower shackle bolt. 30
2. In a lubricating system, a shackle connection including an upper shackle bolt, a lower shackle bolt and links connecting said shackle bolts, each of said shackle bolts having an axial bore and a radial bore com- 35
3. In a lubricating system, in combination with the chassis including a channel member and spring, a shackle connection including an upper shackle bolt mounted on the channel member, a lower shackle bolt engaged with the spring and links having pivotal connection with said shackle bolts, each of said shackle bolts having an axial bore and a radial bore communicating therewith and a peripheral groove communicating with the radial bore, means for supplying lubricant to said shackle bolts including a sleeve arranged 40 on the upper shackle bolt, a lubricant supply pipe disposed in the channel member of the chassis and having a branch connected to and extending through said sleeve and communicating with the peripheral groove of said upper shackle bolt whereby said upper shackle bolt and its bore are supplied with lubricant, and a pipe having threaded connections at its ends with the shackle bolts and directly communicating with the axial bores thereof so as to afford free open and direct communication between the axial bores of the upper and lower shackle bolts whereby the lubricant is supplied to the lower shackle bolt from said upper shackle bolt. 45

municating with each other and a peripheral groove communicating with the radial bore, and means for supplying lubricant to said shackle bolts including a sleeve arranged on said upper shackle bolt, a lubricant supply pipe having a branch connected to and extending through said sleeve and communicating with the peripheral groove of said upper shackle bolt whereby lubricant is supplied to the upper shackle bolt and to the bores thereof and a pipe having direct threaded connection with the ends of the upper and lower shackle bolts and affording free open and direct connection between the axial bores thereof whereby the lubricant is conveyed from the upper shackle bolt to the lower shackle bolt. 55

3. In a lubricating system, in combination with the chassis including a channel member and spring, a shackle connection including an upper shackle bolt mounted on the channel member, a lower shackle bolt engaged with the spring and links having pivotal connection with said shackle bolts, each of said shackle bolts having an axial bore and a radial bore communicating therewith and a peripheral groove communicating with the radial bore, means for supplying lubricant to said shackle bolts including a sleeve arranged 75 on the upper shackle bolt, a lubricant supply pipe disposed in the channel member of the chassis and having a branch connected to and extending through said sleeve and communicating with the peripheral groove of said upper shackle bolt whereby said upper shackle bolt and its bore are supplied with lubricant, and a pipe having threaded connections at its ends with the shackle bolts and directly communicating with the axial bores thereof so as to afford free open and direct communication between the axial bores of the upper and lower shackle bolts whereby the lubricant is supplied to the lower shackle bolt from said upper shackle bolt. 80

PALEMON H. GASKINS.
